IRONING BOARD

Filed Oct. 23, 1928

FIG. 1

FIG. 2.

FIG. 3

Inventor
James G. Haugh
By Chas. Williamson,
Attorney

UNITED STATES PATENT OFFICE

JAMES G. HAUGH, OF BASCOM, OHIO

IRONING BOARD

Application filed October 23, 1928. Serial No. 314,499.

An important object of my invention is a construction of ironing boards with foldable legs or supports which though when opened out for use will have a wide base, nevertheless 5 be compactly folded so that the legs will not only lie close against the board, but will not project laterally thereof, and hence, the whole structure when folded will be within the area of the board itself. This is desirable 10 for a number of reasons. A very important reason is concerned with shipping and handling the boards in transit. Compactness saves shipping space. To have the folded structure no wider than the board enables 15 the same to be wrapped or enclosed in paper sacks or cartons of smaller size than is the case when the collapsed structure is wider and this means less cost of sacks or cartons. Sacks or cartons are used for the protection 20 of the boards from soiling in handling, so as to assure their delivery to the customer in a perfectly clean state. Other objects are to provide a simple and strong structure and one which when opened out and in use will 25 not be in danger of accidental collapse from knocks or blows or thrusts against the legs. The invention consists in whatever is described by or is included within the terms or scope of the appended claims.

30 In the drawings:

Fig. 1 is a perspective view of an ironing board embodying my invention, shown arranged for use;

Fig. 2 is a bottom plan view with the legs 35 folded against the under side of the board, the out-spread position of the legs being shown in dotted lines;

Fig. 3 is a detail view in vertical section through the leg locking means showing the 40 parts when the legs are open for use.

Describing in detail what is shown in the drawings, the ironing board, 10, is of the usual or conventional form. On the under side near the wide end is rigidly secured a 45 transversely extending metal strap, 11, having near each end a down-turned end, 12, set a distance within the adjacent edge of the board slightly greater than the thickness of the leg, 13, which is pivoted thereto by a 50 horizontal headed bolt or screw, 14, and nut,

15. The pair of legs, 13, constitute the supports for the board at the wide end when said legs are opened from a position flat against the under side of the board to a vertical position and when they are in a vertical position they diverge at a substantial angle so that their ends in contact with the floor are much farther apart than the width of the ironing board. Besides their up and down swinging movement on the pivot bolts or 55 screws, they are sufficiently loose upon such bolts or screws to allow side-wise or lateral play which permits them to be moved towards and from one another so that when they are in the opened out position they may be spread apart as shown in Fig. 1, and so that when 60 they are in their folded position as shown in Fig. 2 they will lie wholly within the side edges of the board.

The lateral or side wise movement of the legs 13, thus provided necessitates that they be braced and locked in their spread apart table supporting positions. I, therefore, extend from each leg to the other, two braces which extend obliquely or at an angle and cross each other, each brace being pivoted at its upper end by a pivot, 16, to one leg near its upper end and at its other end by a pivot, 16^a, to the other leg near its lower end. Each brace has between its ends and near its upper 65 end a rule joint 17, which opens to allow the legs to be swung towards each other, but which rigidly locks to form a straight line connection from one leg to the other when the pair of legs are opened out to vertical 70 board supporting position. By the described arrangement of the braces they are sufficiently high above the floor as not to be in danger of being struck by the foot of a person or by a child crawling on the floor or playing on 75 the floor around the ironing board, and thus, there is no danger of accidental closing or collapse of the braces and of the legs braced 80 thereby.

Also pivoted on each of the pivot bolts or 85 screws, 14, are the upper ends of two bars, 18, which extend longitudinally of the board towards the narrow end thereof and which are brought together at their free ends and joined so as to make a single foot or floor en- 90 95 100

gaging piece that will stand at a point midway between the sides of the board thus providing what in effect is a V-shaped leg whose upper spread apart ends are adapted to contact with the under side of the board near the wide end when such leg is in opened out supporting position. Said leg when folded lies flat against the under side of the board in the space between the two end legs, 13.

10 Besides the braces which hold the legs, 13, in their spread apart vertical position, each of such legs has pivoted to it on its inner side one end of a bar, 19, which extends rearwardly from the leg and the two bars, 19, thus provided are rigidly joined at their upper ends by a sheet metal plate, 20, that is adapted to bear against the under side of the ironing table or board at substantially mid-length thereof and to interlock with a thin bar, 21, secured to the under side of the table or board with a free end of which interlocks a cross bar, 22, on said plate formed by a transverse slot therein. When thus interlocked said plate and the brace bars connected therewith are held immovable by a latch and brace bar, 23, which is pivoted at its lower end between the converging leg forming bars, 18, and when the table is opened out extends upwardly and forwardly and by a notch, 24, 30 at its upper end engages said plate.

The two rearwardly extending brace bars, 23, converge as they extend rearward from the front legs so as to have them take the minimum amount of room transversely of the ironing board both when opened out for use and collapsed. These brace bars, 23, when the legs are folded against the underside of the board lie between the end legs and the V-shaped leg and flat against the under side of the board and they have sufficient lateral spring or play to enable them to accommodate their positions to the positions of the end legs when spread apart as in use or when moved towards one another to bring them within the limits of the sides of the board. It will be seen that when opening out the legs, the converging brace bars, 23, moving towards the wider end of the V-shape leg and contacting with the outer sides thereof are automatically spread outwards, and, therefore, automatically force outwards or spread apart, the end legs, 13, and thus straighten out the jointed braces. This makes unnecessary any hand manipulation of those braces to straighten them out.

It will be observed, first, that all of the supporting members including the brace elements are of rigid material and construction, 60 there being no transversely flexible elements such as cords or chains; and, second, that all of the members which require movement to collapse them are sufficiently high above the floor that there is no danger by striking with 65 foot or bumping against by person to displace

them, and cause the serious collapse of the ironing board.

What I claim is:

1. An ironing board having a plurality of spaced-apart floor-engaging members that include a pair of legs, means pivoting the legs to the under side thereof for movement towards and from one another between positions in which they lie lengthwise against the under side of the board, and a vertical position, and a pair of braces each extending from one leg to the opposite leg in an oblique direction, said legs at their point of pivotal connection with the board being movable to a limited extent towards and from one another, whereby when they are in an opened position they may be spread at their floor-engaging ends substantially farther apart than the width of the ironing board and when in a position folded against the board lie wholly within the wide edges of the board. 75 80 85

2. An ironing board having a plurality of spaced-apart floor-engaging members that include a pair of legs, means pivoting the legs to the under side thereof for movement towards and from one another between positions in which they lie lengthwise against the under side of the board, and a vertical position, and a pair of braces each extending from one leg to the opposite leg in an oblique direction, said legs at their point of pivotal connection with the board being movable to a limited extent towards and from one another, whereby when they are in an opened position they may be spread at their floor-engaging ends substantially farther apart than the width of the ironing board and when in a position folded against the board lie wholly within the wide edges of the board, and brace bars pivoted to said legs and extending therefrom longitudinally of the board and means to secure the free ends of said brace bars to the under side of the board. 90 95 100 105

3. An ironing table having a pair of legs pivoted to its under side near one end, a leg device comprising a pair of bars also pivoted at their ends at the same end and extending lengthwise of the board, a pair of converging braces extending from said legs lengthwise of the board, a plate securing said braces at their converging ends and a lock and brace bar pivoted at one end to said leg device and having a notch at its other end for interlocking with said plate. 110 115

4. An ironing table having a plurality of spaced-apart floor-engaging members that include a pair of legs pivoted near one end thereof, means connecting them to the table for movement towards and from one another, a leg device comprising a pair of bars also pivoted to the same part of the table and converging towards the other end of the table and a pair of braces connected at one end with said pair of legs and straddling said leg device secured together at their other ends to 120 125 130

the board, and adapted by movement along the same to be spread apart and thereby to impart spreading apart movement to said pair of legs.

5. An ironing table having a plurality of spaced-apart floor-engaging members that include a pair of legs pivoted near one end thereof, means connecting them to the table for movement towards and from one another, a leg device comprising a pair of bars also pivoted to the same part of the table and converging towards the other end of the table and a pair of braces connected at one end with said pair of legs and straddling said leg device secured together at their other ends to the board, and adapted by movement along the same to be spread apart and thereby to impart spreading apart movement to said pair of legs, and jointed braces connecting said pair of legs.

10 20 In testimony whereof I hereunto affix my signature.

JAMES G. HAUGH.
